United States Patent Office

Des. 206,532

Patented Dec. 27, 1966

206,532

DENTAL CHAIR OR SIMILAR ARTICLE

John M. Gardella and Rudolph Vetere, Staten Island, N.Y., assignors to The S. S. White Dental Manufacturing Company, Philadelphia, Pa., a corporation of Pennsylvania

Filed July 27, 1965, Ser. No. 86,308

Term of patent 14 years

(Cl. D15—3)

FIG.3

FIG.7

FIG.8

FIGURE 1 is a perspective view of a dental chair or similar article, showing our design;

FIGURE 6 is a side perspective view thereof, with the back rest in a partially lowered position, and the leg rest in a partially raised position;

FIGURE 7 is a side perspective view thereof, with the back rest in a fully lowered position, and the leg rest in a fully raised position; and

The dominant features of the design reside in the portions shown in full lines.

We claim:

The ornamental design for a dental chair or similar article, as shown and described.
